GUSTAV LEONARD FISK, OF PITTSBURGH, PENNSYLVANIA, ASSIGNOR TO MESTA MACHINE COMPANY, OF PITTSBURGH, PENNSYLVANIA, A CORPORATION OF PENNSYLVANIA

COOLING BED

Application filed December 17, 1929. Serial No. 414,752.

The present invention relates to cooling beds for hot metal bars and particularly to cooling beds designed and constructed to handle rolled bars of rectangular cross section, such as are used in the manufacture of springs, when cut into suitable lengths.

By means of a cooling bed constructed in accordance with the principles of this invention the highly heated elongated bars of rectangular cross section, the product of a rolling mill producing "spring flats" or the like, which bars are incapable of standing on edge without lateral support, are mechanically assembled into a pack, in which pack each remains while slowly and uniformly cooling to an approximately predetermined temperature, and from which pack the cooled and perfectly annealed bars are ultimately automatically discharged. The pack comprises a plurality of bars arranged in parallelism and standing on edge, each bar being supported by an adjacent bar, the pack being maintained of substantially uniform thickness and each bar passing progressively therethrough from one side to the other, hot bars being periodically added to one side and cooled bars periodically discharged from the other. The invention contemplates a novel means for and method of initially forming the pack, novel means for adjusting the bed for the accommodation of bars of different cross sectional shapes and dimensions, and numerous other features of importance, all of which will be hereinafter pointed out and fully described.

The drawings illustrate a form of the invention which is practical and efficient, but it will be obvious to those skilled in the art that many changes can be made in details without departing from the principles of the invention or in the scope of the invention as set forth in the claims appended hereto. Referring to the drawings:-

Fig. 1 is a partial plan view;
Fig. 2 is a vertical sectional view taken on line 2-2 of Fig. 1;

Fig. 3 is a view similar to Fig. 2, but showing certain parts of the mechanism in different positions;

Figs. 4 to 11 are rather diagrammatic

views illustrating different stages in the formation of the pack.

The apparatus illustrated consists of a primary section A on which the hot bars received from the rolling mill (not shown) are handled to form a pack, and a secondary section B to which the bars discharged from the pack are successively delivered and across which they are moved to a "run out" mechanism by means of which they are transferred to fabricating machines or the like.

The primary section A includes a run-in table composed of aprons 10 and rollers 11, the latter being positively rotated by suitable known means (not shown) to move the bars endwise as they come from the rolling mill into proper position for broadside movement on to the cooling bed. When a bar reaches this position, it is shoved or kicked off the run-in table by kick-off arms 12. These arms are pivoted to lever arms 13 fast on a shaft 14 which is adapted to be oscillated by known mechanism.

Extending alongside the run-in table is a downwardly inclined table comprising two sections, a skid section 15 down which the bars slide by gravity and a second section 16 of gentle slope across which the bars are adapted to be positively propelled in pack formation as hereinafter described. As shown, this inclined table is formed of castings having smooth continuous upper surfaces, but obviously it might be formed of suitably spaced skid bars. Between the sections 15 and 16 of the table is a rectangular depression, or pocket, 17 adapted to receive a plurality of bars.

The inclined table has a number of parallel slots 18 which intersect the pocket 17 and are disposed at right angles thereto, and operating in each slot is a supporting arm 19 which is adjustably mounted so that it can be rotated about a pivot and can also be shifted longitudinally, for a purpose hereinafter explained. To provide for these adjustments, the arms 19 are mounted at their rear ends on eccentrics 20 carried by a shaft 21 and at their front ends they are pivoted to the upper ends of links 22, the lower ends of which are pivot-

ed to the cranks of a shaft 23. By rotating shaft 23 the arms can be raised from the position shown in Fig. 2 to the position shown in Fig. 3, and then by rotating the eccentric shaft 21 the arms can be shifted longitudinally to the position shown in Fig. 7.

Rocking skids 24 operate through slots 25 formed in the lower marginal portion of table section 15 and in the rear wall of pocket 17, and these skids are adapted to be projected over the pocket 17, as shown in Fig. 2, or to be retracted therefrom, as shown in Fig. 3. These skids are secured to a shaft 24' rigid with which is a depending arm 26 connected by a link 27 to suitable operating mechanism, not shown. The function of the rocking skids is to make certain that bars having a substantially smaller width than the width of pocket 17 will be received in the latter in a flatwise position, the skids being adjusted to vary the effective width of the pocket opening in accordance with the width of the bars.

Also associated with the primary section A of the cooling bed are a number of pusher bars 29 which are adapted to be reciprocated, through grooves formed in the lower marginal portion of table section 15, from the normal position shown in Figs. 2 and 3 to the position shown in Fig. 9, or to the extreme position shown in dotted lines P in Fig. 3. The forward ends of these pusher bars are supported in the grooves 30' and in grooves 30 formed in the table section 16, and their rear ends are pivoted to upstanding arms 31 secured to a shaft 32 which may be oscillated by any suitable mechanism (not shown).

The secondary section B of the cooling bed comprises a plurality of pairs of shuffle bars 33 and 34 and a run-out table composed of aprons 35 and rollers 36. The scuffle bars are constructed and operated in a well known manner. The bars of each pair are supported at their rear ends respectively on two eccentricities carried by a shaft 37 and their forward ends are freely slideable on rollers mounted on arms 38 which are secured to a revoluble shaft 39. The two eccentricities carrying the rear ends of the bars are angularly displaced from each other 180°, so that when the shaft 37 is rotating the bars move in opposite directions with a circular motion having vertical and horizontal components, whereby the rolled bars delivered broadside on to the shuffle bars are carried by the latter alternately in a step by step movement. This movement of the shuffle bars, when they are raised as shown in dotted lines in Fig. 3, carries the rolled bars to the proper position over rollers 36; the shuffle bars are then lowered to the position shown in full lines, Figs. 2 and 3, whereupon the rolled bars will be deposited on rollers 36 to be conveyed to suitable fabricating mechanism.

The cooling bed above described is adapted

to carry out a continuous process of pack annealing in the following manner: Prior to the commencement of the process, the mechanism is adjusted so that the pusher bars 29 are retracted to the position shown in Figs. 2 and 3; the arms 19 are raised to a position about midway between their extreme upper and lower positions, as indicated in Fig. 4, with the eccentricities 20 in the position shown in Figs. 2 to 6; and the rocking skids 24 are projected over the pocket 17 as required by the width of the bars to be formed into a pack. When the first bar from the mill has reached the proper position on the run-in table, the kick-off arms 12 are operated to shove it laterally onto the skid section 15 and it will slide down this section and come to rest flatwise in pocket 17, being supported therein by arms 19 (see Fig. 4). Since the rocking skids 24 are adjusted to make the effective opening of the pocket only slightly wider than the width of the bar there will be no likelihood that the latter will be deposited on the arms 19 in other than a flatwise position. The shaft 23 will next be turned by manual control or by automatic means through an angle of a few degrees to lower arms 19, so that the bar carried thereby will be lowered through a distance about equal to its thickness. The next bar discharged onto the skid section will in a like manner be deposited in the pocket, coming to rest on top of the first bar and in registry therewith. These operations will be repeated with each successive bar, until a stack 40 of required height has been built in the pocket 17.

Next the shaft 23 is turned to the position shown in Fig. 3, to raise the arms 19 to the level of table section 16. This raises the stack 40 out of the slot and effectively closes the slot to the further entry of bars (see Fig. 6). The eccentric shaft 21 is now turned through an angle of 180° or less, causing the supporting arms 19 to be shifted longitudinally to the position shown in Fig. 7 and bringing the stack 40 close to the lower end of skid section 15, in proper position to act as a stop for the next bar. The next bar will therefore be brought to rest in the position shown in Fig. 8, that is, in an inclined position with its lower edge abutting the stack 40. Next shaft 32 is turned through a small angle to move the pusher bars 29 from the position shown in Figs. 2 and 8 to the position shown in Fig. 9, thereby turning the inclined bar to a position flush against the stack 40 and moving the bar and stack a slight distance down the inclined table section 16. For each successive bar sliding down skid section 15 the pusher bars 29 will be operated through the same stroke to place the bar on edge and to move the group of previously deposited bars a step along table section 16.

Eventually a pack of bars standing on edge will be formed as shown in Fig. 10, and on the addition of a few more bars to the pack the first formed abutment stack 40 will fall 5 from the edge of table section 16 on to the shuffle bars 33 and 34 and will be conveyed as hereinbefore described.

It is to be observed that the stack 40 functions merely as a temporary abutment for the 10 pack standing on edge and is therefore formed only in the initial stage of the process. When the pack standing on edge has been deprived of the support of the abutment stack, a few of the bars at the discharge end 15 of the pack will tip over and form a sufficient abutment for the remainder of the pack (see Fig. 11). As bars are added to the pack at the one end bars will be discharged from the other end on to the shuffle bars, at 20 substantially the same rate, so that the number of bars in the formed pack will remain substantially constant. The process is therefore a continuous one. Each bar will change its position in the pack progressively 25 with a step by step movement, travelling gradually along the inclined table section 16 and being slowly cooled with bars on either side to render gradual and uniform its rate of cooling. Each bar being subjected to 30 exactly the same conditions, all the bars will be rendered uniform as to temper and form. When it is desired to discontinue the pack annealing process, the pack of bars on table section 16 are bodily removed from said section 35 and deposited on the shuffle bars. This is accomplished by giving the pusher bars 29 a long stroke, by turning shaft 32 through a sufficient angle to move said bars to the extreme position shown in dotted lines on 40 Fig. 3.

Rectangular bars of square and other cross sections, which do not require lateral support can also be pack annealed on the cooling bed above described. Since it is unnecessary to form an abutment stack when operating on such bars, the supporting arms 19 will be maintained in the position shown in Fig. 45 3, wherein they close the pocket 17 to the entry of bars. Otherwise the operations will 50 be the same as described with reference to the pack annealing of spring flats.

Obviously the cooling bed described can be used for the cooling of bars singly as well as in pack formation. However, to 55 adapt it for such use there should be provided a cooling bed section between the table section 16 and the shuffle bars, the latter, of course, being separated from the section 16 to accommodate such a cooling bed section. 60 Any common form of cooling bed section can be used for this purpose, such for example, as that shown in U. S. patent to Hellstrom No. 816,323. The bars would be discharged from this cooling bed section on to the shuffle 65 bars where they would be handled in the

manner heretofore described. The delivery of rolled bars to the bed section for cooling in spaced formation may be carried out in the following manners:—

A round kicked from the run-in table will 70 slide down the skid section 15 into the pocket 17 and will be lifted out of said pocket by raising arms 19, whereupon it will roll by gravity down the section 16 and on to the bed section for cooling in spaced formation. By 75 maintaining the arms 19 in their upper position, the round can, if desired, be caused to roll uninterruptedly down the skid section 15 and table section 16. In the case of a small round which does not readily roll 80 on the gentle slope of section 16, it may be stopped in pocket 17, then raised to the level of section 16 and pushed over this section by operating pusher bars 29. Bars of square or irregular sections may be stopped in pocket 17, then raised to the level of section 16 and pushed over this section by the pusher bars. 85

Now having fully described my invention, what I claim as new and desire to secure by Letters Patent is:

1. A cooling bed comprising a skid section and a table section and having an elongated depressed portion, or pocket between said sections for the reception and temporary storage of a plurality of bars sliding successively down said skid section, a plurality of arms extending across said pocket adapted to support bars therein, means for raising and lowering said arms, and pusher bars adapted to propel bars over said table section. 95

2. A cooling bed comprising a skid section and a table section and having an elongated depressed portion, or pocket, between said sections adapted to receive bars sliding down said skid section, adjustable skids adapted to be projected over said pocket to vary the effective opening thereof in accordance with the width of the bars, and means independent of the table section for raising bars out of said pocket to the level of said table section. 105

3. A cooling bed comprising a skid section and a table section and having an elongated depressed portion, or pocket, between said sections adapted to receive bars from said skid section, rockable skids adapted to be projected over said pocket to adjust the effective opening thereof, means independent of the table section for raising bars out of said pocket to the level of said table section, and means for pushing bars over said table section. 110

4. In combination with the run-in table from a rolling mill, a cooling bed comprising a table having a relatively steep section down which the hot bars discharged broad-side from the run-in table slide by gravity and having a section of gentle slope and having an elongated depressed portion, or 120 125

5 pocket, between said sections adapted to receive and temporarily store a plurality of bars sliding successively thereinto from said steep section, a plurality of spaced arms 10 extending across said pocket adapted to support bars therein, said arms being independent of said table section, means for raising and lowering said arms, means to propel bars over said section of gentle slope, and means 15 to convey the bars from said last mentioned section to suitable fabricating mechanism.

5. In combination with the run-in table from a rolling mill, a cooling bed comprising a table having a relatively steep section down 15 which the hot bars discharged broadside from the run-in table slide by gravity and having a section of gentle slope and having a depressed portion, or pocket, between said sections, supporting arms extending across 20 said pocket, means for lowering said arms to permit the accumulation in said pocket of a stack of bars lying on their sides and for raising said arms to bring said stack to the level of said section of gentle slope, and 25 pusher bars for turning succeeding bars to an edgewise position and moving said bars and pack step by step along said section of gentle slope.

6. A cooling bed for pack annealing flat 30 bars comprising a skid section down which hot bars are adapted to slide broadside from the run-in table from a rolling mill and a table section along which the bars are progressively moved in a pack, said bed having 35 a depressed portion, or pocket, between said sections adapted to receive bars from said skid section and to accumulate a stack of bars lying on their sides, means to close said pocket to the further entry of bars and to raise 40 said stack to the level of said table section to act as an abutment to succeeding bars, and intermittently operating means to turn succeeding bars to an edgewise position and to move said bars and pack step by step along 45 said table section.

7. A cooling bed for pack annealing flat bars comprising a skid section down which hot bars are adapted to slide broadside from the run-in table from a rolling mill and a 50 table section along which bars are progressively moved in pack formation, said bed having a depressed portion, or pocket, between said sections adapted to receive bars from said skid section and to accumulate a 55 stack of bars lying on their sides, rocking skids adapted to be projected from the lower edge of said skid section partially over said pocket to vary the opening thereof in accordance with the width of the bars, a plurality of spaced arms extending across said 60 pocket adapted to support said stack, means for raising said arms to bring the stack to the level of said table section, means for shifting said arms longitudinally to bring 65 said stack close to the lower end of said skid

section to act as an abutment and support for succeeding bars, and intermittently operating means to turn succeeding bars to an edgewise position and to move said bars and stack step by step along said table section. 70

8. A cooling bed for pack annealing flat bars comprising a table having a depressed portion, or pocket, means for discharging bars from the run-in table from a rolling mill into said pocket to form a stack of bars therein lying on their sides, means to raise said stack to the level of said table and close said pocket to the further entry of bars, and means to turn succeeding bars to an edgewise position and move said bars and stack step by step along said table section, said stack acting as a temporary lateral support for the bars standing on edge. 75

9. In combination with a cooling bed having an elongated pocket adapted to receive bars of rectangular cross section from the run-in table from a rolling mill and accumulate a stack of bars lying on their sides, a plurality of spaced arms extending across said pocket, means for raising and lowering said arms about a pivot and means for adjusting the pivotal axis of said arms so that they may be shifted longitudinally. 80

10. In combination with a cooling bed having an elongated pocket adapted to receive bars of rectangular cross section from the run-in table of a rolling mill and accumulate a stack of bars lying on their sides, means for adjusting the opening of said pocket in accordance with the width of the bars, a plurality of spaced arms extending across said pocket and adapted to engage and support a pack of bars, means for raising and lowering said arms about a pivot, and means for adjusting the pivotal axis of 90 said arms. 100

11. In combination with a cooling bed having a skid section and a table section and having an elongated pocket between said sections adapted to receive bars from said skid section, arms extending across said pocket, a shaft having eccentrics on which corresponding ends of said arms are pivoted, and a shaft journaled beneath said arms and having cranks connected to the other ends 110 of said arms. 115

12. The method of pack annealing flat bars which do not stand on edge without lateral support, which consists in forming a stack of bars lying on their sides from the first bars coming from the mill, turning succeeding bars on edge successively and feeding them forward step by step while supported by said stack to form a pack standing on edge, withdrawing the stack when said pack has attained a predetermined size and thereafter withdrawing bars from the front side of the pack at substantially the same rate as bars are added at the rear side thereof. 120 125 130

13. A cooling bed for bars which will not stand on edge without lateral support comprising in combination, a table section, means for forming a stack of bars on said table section, the bars of said stack being substantially horizontally disposed and superposed one upon the other, and means for forming a pack of bars standing on edge on said table, said pack being supported during its formation by said stack. 70
14. The method of pack annealing bars which will not stand on edge without lateral support comprising, forming a stack of bars which rest horizontally upon a support and are superposed one upon the other, building up a pack of bars resting on edge by placing said bars on the support in such manner as to be supported against overturning by said stack, and in continuously adding heated bars to one side of the pack thus formed and withdrawing them from the other. 75
15. A cooling bed comprising a skid section and a table section and having a depressed portion, or pocket, between said sections adapted to receive and form into a stack, a plurality of bars of rectangular cross section which successively slide down said skid section, means independent of the table for raising the stack of bars thus formed out of said pocket to the level of said table section, and means for propelling bars over said table section. 80
16. A cooling bed comprising a skid section and a table section and having an elongated depressed portion, or pocket, between said sections adapted to receive bars of rectangular cross section successively sliding down said skid section and to form them into a stack of superposed bars, and means independent of the table to raise the stack of superposed bars out of said pocket to the level of said table section. 85
17. A cooling bed for pack annealing bars which will not stand on edge without lateral support comprising, in combination, a table having a bar receiving surface, means for accumulating a plurality of bars as they come from a mill into a stack of horizontally disposed superposed bars and depositing the stack on the table, and means for building up a pack of bars on edge, resting against said stack and intermittently advancing the stack and pack. 90
18. A cooling bed for pack annealing bars which will not stand on edge without lateral support comprising, in combination, a table having a bar receiving surface, means for establishing on the table as a preliminary step a stack of horizontally disposed superposed bars, and means for building up against said stack a pack of bars standing on edge and intermittently advancing the stack and pack. 95
19. A cooling bed comprising a skid section and a table section and having a pocket between said sections, said pocket having a vertically adjustable bottom, and means for intermittently lowering said bottom as bars are deposited therein, for the purpose of forming a stack of horizontally disposed superposed bars. 100
20. A cooling bed comprising a skid section and a table section and having a pocket between said sections, said pocket having a vertically adjustable bottom, and means for intermittently lowering said bottom as bars are deposited therein, for the purpose of forming a stack of horizontally disposed superposed bars and for thereafter elevating the completed stack to the level of the upper surface of the table section. 105
21. A cooling bed comprising a skid section and a table section and having a pocket between said sections, said pocket having a vertically adjustable bottom, means for intermittently lowering said bottom as bars are deposited therein, for the purpose of forming a stack of horizontally disposed superposed bars and for thereafter elevating the completed stack to the level of the upper surface of the table section, and laterally reciprocable members for pushing the stack from said bottom onto the surface of the table. 110
